UNITED STATES PATENT OFFICE.

AUGUSTA ROTH, OF CLEVELAND, OHIO.

COMBINED CORSELET AND BRASSIÈRE.

Application filed September 18, 1927. Serial No. 219,879.

This invention as indicated relates to an improved combined corselet and brassière. More particularly it comprises a corset or corselet portion of the garment formed of a 5 rearward section of flexible material suitably stayed and a forward section of lesser extent and adapted to support the lower abdomen and formed of suitably stayed elastic material across the major portion thereof, said 10 two sections being adapted to be adjustably secured at their lateral edges by a lacing or similar fastening means, and a brassière portion of the garment formed of a rearward section attached along its lower edge to the 15 rearward portion of the corset proper along a transverse line adjacent the waist of said last-named portion.

The principal object of the present invention is to provide an improved supporting garment for women's wear designed to maintain the symmetrical lines of the figure without causing discomfort to the wearer under any conditions of use and irrespective of whether the user is in repose or actively 25 moving about.

Another object of the invention is to provide an improved supporting garment which will support the fleshy portions of the figure about the waist line and beneath the 30 arms and hold the same in proper symmetrical relation to adjacent parts of the body of the wearer. A further object of the invention is to provide an improved supporting garment for women's wear which will 35 permit outer garments to be worn without being drawn out of proper position or caused to cling to the figure of the wearer at points where the same should engage in free contact without binding. Other and 40 further objects of the invention will appear in the course of the following description. To the accomplishment of the foregoing and related ends, said invention, then, consists of the means hereinafter fully described 45 and particularly pointed out in the claims.

The annexed drawing and the following description set forth in detail certain structure embodying the invention, such disclosed means constituting, however, but one 50 of various structural forms in which the principle of the invention may be used.

In said annexed drawings:

Fig. 1 is a perspective view of a supporting garment embodying the principles of my invention, shown applied to the figure 55 of a woman, the lower portion of the for-

ward section of the brassière being cut away; Figs. 2 and 3 are rear and side views respectively, of the garment shown in Fig. 1, as applied to the figure of a woman; 60 Fig. 4 is a front elevation of the supporting garment in spread apart position; and Fig. 5 is a view similar to Fig. 4, but showing the supporting garment as viewed in rear elevation.

As will more clearly appear from the drawings, the figure supporting garment comprises a corselet portion 1 and a brassière portion 2. The corselet is provided with a rearward portion 3 suitably stayed 70 by vertical stiffening members 4 and shaped to the contour of the hips adjacent the lower central portion 5. The stiffening members preferably terminate at points spaced from the lower edge of the section.

The rearward portion of the corset section of the garment extends to a point somewhat more than half-way about the body of the wearer, thus bringing the vertical edges 6 of said portion to a point well advanced 80 along the thighs of the wearer. Adjustable hose supporting elastic strips 7 are secured to the lower front edges of said rearward section and may be fastened to the adjacent upper edge of the hose 8.

The vertical margins of the rearward portion of the corselet are provided at a central portion with a series of eyelets 9 through which corset laces 11 may be engaged to secure to said rearward section the forward 90 or abdominal section of the corselet 12 which is provided with a corresponding series of eyelets 13 along each vertical edge.

The abdominal section of the corselet is preferably formed of a central portion 14 of elastic material and non-elastic fabric marginal strips 15, within which the lacing eyelets 13 are engaged. Suitable stays or vertical stiffening members 16 may be provided at spaced positions across the abdominal section of the corselet. The lower edge 17 of the abdominal section preferably is curved downwardly to engage the lower abdomen.

Hose supporters 18 are also provided adjacent the lower corners of the abdominal section of the garment and may be attached to the hose closely adjacent the hose supporters 7 first mentioned. The hose supporters 18 last referred to are secured to the 100 non-elastic side portions 15 of the abdominal section which extend along each vertical

marginal portion of said section. Said hose supporters are provided with longer elastic portions than those attached to the rearward portion of the corset inasmuch as the abdominal section thereof terminates at a point which is much higher upon the body of the wearer than that last described.

The brassière portion of the garment is permanently attached to the corselet and 10 comprises a rearward section 19 and a forward section 20 united to each other by means of a plurality of elastic strips 21, 22, 23. The rearward portion of the brassière is preferably of rectangular shape and of 15 slightly greater vertical than horizontal extent. The lower edge 24 as stated is securely sewed to the rearward portion of the corset and shoulder straps 25 are engaged at their ends with the upper corners of said 20 panel. The lower side edges of the panel have secured thereto the ends of the elastic strips 21, 22 and 23, which have their end portions disposed at an angle so that the body portions of said strips will slope downwardly from said back panel of the brassière. Said strips extend from the back panel to a position at approximately the middle of the respective sides of the body of the wearer, and said strips thus overlie the rearward parts of the sides of the body. The 30 opposite ends of said respective sets of elastic strips on the two lower strips 22, 23, are cut at substantially the same angle as the ends first mentioned, while the upper strip 35 21 is cut in the opposite direction, thus conforming to the outline of the figure when attached to the adjacent parts. The ends of the elastic strips which pass beneath the left arm in the specimen illustrated are permanently secured at their free ends to the forward portion of the brassière which comprises a panel 26 shaped to the figure by means of darts 27 extending inwardly from the top edge and having the side portions 45 28 cut away adjacent their upper edges to provide ample clearance for the arms.

To each of the upper corners of the forward portion of the brassière, the shoulder straps 25 heretofore mentioned, are secured by stitching or in any other suitable manner. The elastic strips which are passed beneath the right arm, in the specimen garment illustrated, are provided on their free ends with eyelets 31 adapted to cooperate with hooks 32 attached to the margin of the forward portion of the brassière at a suitable point. Beneath the point of attachment of the elastic straps, the brassière is cut inwardly to carry the lower marginal portions 33 thereof away from the hip joints of the wearer so as to prevent interference with the free motion of the limbs when in a stooping or sitting posture.

The forward portion of the brassière also 60 carries a pair of elastic hose supporter strips

34 attached adjacent its lower corners which are adapted to be engaged with the hose approximately at the central forward edge of said hose. Thus the three supporters described will be engaged with the upper edge 70 of the hose in close juxtaposition along the outer forward quadrants of said hose.

The garment above described is of particular value for women having a tendency toward stoutness inasmuch as the excess flesh 75 across the abdomen will be engaged and held in position by means of the elastic abdominal section and the excess flesh below the shoulder blades and beneath the rearward portion of the arms will be firmly held in a 80 position upwardly from the waist line.

One of the special features of the garment resides in the fact that the excess flesh is taken care of by resilient members and provides for a figure with clean cut symmetrical lines without causing any discomfort to the wearer. The shaping of the ends of the elastic strips which pass beneath the arms of the wearer provides for a shaping of the figure at the points where such strips engage 90 the same and distribute the flesh which ordinarily interferes with the symmetrical contour of the figure at this point and holds the same in conformity with the outlines of the figure adjacent thereto. 95

Other modes of applying the principle of my invention may be employed instead of the one explained, change being made as regards the structure herein disclosed, provided the means stated by any of the following claims or the equivalent of such stated means be employed. 100

I therefore particularly point out and distinctly claim as my invention:

1. An article of the character described 105 having in combination a corset section provided with a stayed rearward portion and an abdominal portion secured at its side edges thereto, and a brassière surrounding the body of the wearer and overlying the upper stayed rearward portion of the corset secured at its lower edge only to the central portion of the back of said rearward portion and having a forward section adapted to be engaged over said abdominal portion 110 115 of the corset section.

2. An article of the character described having in combination a corset section provided with a stayed rearward portion and an abdominal portion secured at its side 120 edges thereto, and a brassière surrounding the body of the wearer and overlying the upper stayed rearward portion of the corset having a rear section secured at its lower edge only to the central portion of the back of said rearward portion and having a forward section united to said rear section by elastic members and adapted to be engaged over said abdominal portion of the corset 125 section. 130

3. An article of the character described having in combination a corset section having an elongated portion adapted to be engaged over the back and sides of the wearer and a relatively narrow abdominal portion of elastic material, and a brassière section having a rearward panel permanently attached at its lower edge adjacent the waist-line of the rearward corset section and having a forward portion adapted to overlie substantially the entire forward portion of the body of the wearer, said rearward panel being attached to the forward portion by means of a plurality of elastic strips angularly disposed and shaped to support the figure of the wearer beneath the arms and immediately above the waist-line. 45
4. An article of the character described having in combination a corset section having an elongated portion adapted to be engaged over the back and sides of the wearer and a relatively narrow abdominal portion of elastic material, and a brassière section having a rearward panel permanently attached at its lower edge adjacent the waist-line of the rearward corset section and having a forward portion adapted to overlie substantially the entire forward portion of the body of the wearer, and a plurality of parallel elastic strips disposed beneath the arms of the wearer and extending angularly downwardly and forwardly from said panel section to said forward section, said strips being shaped at their ends to provide a support for the figure of the wearer immediately above the waist-line. 50
5. An article of the character described having in combination a corset section having an elongated portion adapted to engage about the rear and side portions of the wearer's body, an abdominal portion adjustably secured thereto and adapted to extend across the abdomen, a brassière having a back panel permanently attached at its lower edge adjacent the waist-line to said corset section and disposed over the rearward corset section, and connected with a forward section by means of a plurality of elastic strips, said forward section conforming to the figure of the wearer. 55
6. A combined corset and brassière, said corset comprising a rearward portion of a length extending from the seat of the wearer upwardly to a point just below the shoulder blades, and an abdominal portion adapted to engage the lower abdomen and adjustably secured at its margin to said rearward portion, said brassière portion being secured only along a substantially central transverse line to said corset portion, the rearward portion of said brassière being of substantially rectangular shape and secured by a series of elastic straps to an enlarged forward portion adapted to overlie said abdominal section of the corset and to protect the upper portion of the body of the wearer. 60
7. A brassière comprising a back panel overlying the upper portion of the back of the wearer, a plurality of elastic bands at the lower portion of the side edges thereof, 70 said bands all sloping downwardly from the back to front and extending from the back panel to a position at approximately the middle of the respective sides of the body of the wearer, the upper band having upwardly diverged ends and the lower bands diverging downwardly at their ends to conform to the waist contour, and an enlarged front portion adapted to extend over the forward portion of the figure of the wearer and connected at its respective side portions to said elastic bands. 75

Signed by me this 8th day of September, 1927.

AUGUSTA ROTH.
